DISPLAY SUPPORT

Alan E. Pradt, Neenah, Wis., assignor to Marathon Paper Mills Company, Rothschild, Wis., a corporation of Wisconsin

Application June 28, 1937, Serial No. 150,753

3 Claims. (Cl. 248—37)

This invention relates to a display support for retaining objects for display purposes such as printed cards, posters, price tags, cartons or other objects of light weight. The support made according to this invention is adapted to be removably affixed to any desired supporting surface and it also removably retains the object to be displayed. The display support is affixed to the supporting surface by mere pressure of the fingers and it can be readily removed by peeling it off the support.

Further details and advantages of the invention will be apparent from the specification and drawing, wherein,

Figure 1 is a plan view of the blank for forming the display support.

Figure 2 is a perspective view of the display support in partially set up condition.

Figure 3 is a perspective view of the completely set up display support.

Figure 4 is a sectional view showing the display support retaining a display card.

Figure 5 is a sectional view taken on lines 5—5 of Figure 4, and

Figure 6 is a plan view of a modified form of the blank for forming the display support.

Referring to Figure 1, the display unit is made from a single sheet 9 of cardboard and the like, which is scored along line 14 to form a flange portion 12 and a hinged triangular portion 8 which serves to reinforce the flange when the unit is set up. Tab 25 is hinged at one end of the flange 12 along score line 22. The base of the triangular portion 8 has hingedly connected thereto along score line 15 a tab 30.

Tab 25 is provided with two parallel slits 18 and 20 for a purpose to be explained later. Tab 30 is provided with a cut out portion 32.

One face of flange 12 and tab 25 forming an extension thereof is coated with a suitable pressure sensitive adhesive composition 13.

I prefer to use a hot melt pressure sensitive composition. This composition consists essentially of a cohesive agent, an adhesive agent, a plasticizer and a modifier. The following composition is suitable for use on display units made of cardboard.

Per cent by weight

Rubber	15
Vistanex (isobutylene polymer)	15
Amorphous wax (M. P. 155° F.)	19
Methyl abietate	25
Ester gum	25
Glycerine	0.5
Hydroquinone	0.5

The composition is preferably heated to about 180-200° F. and is applied to the base sheet by means of a roll or doctor blade heated to about 180-200° F. so as to spread a thin layer of the composition of suitable thickness on the base sheet. The base sheet is preferably supported on a heated roll coacting with the spreader roll and spaced away sufficiently to permit the desired thickness of coating to be applied. After the adhesive coating is spread it is congealed by passing the web over a chilled roll and a cover strip is applied lightly thereto. This method and apparatus for carrying same out is disclosed in copending application Serial No. 99,648 which matured to Patent No. 2,089,525, dated August 10, 1937.

The pressure sensitive adhesive coating is protected by a peelable cover strip 10. The cover strip may be made of holland cloth, glassine, parchment paper and the like which will adhere to the adhesive coating but will readily peel therefrom. The cover strip is coextensive with flange 12 and tab 25. One margin 17 of the cover strip extends beyond the score line 14 so as to afford a grasping edge for the cover strip.

In setting up the display support, flange 12 is bent at right angles to the portion 8 along score line 14 as shown in Figure 2. The extending margin 17 of the cover strip can then be readily grasped by the fingers and peeled off the adhesive coating 13. Tab 25 is then folded on score line 22 at right angles to flange 12 and tab 30 is folded thereover and pressed into engagement therewith. Tab 25 will be retained in this overlapped relation since tab 25 has a coating of pressure sensitive adhesive. The two slits 18 and 20 previously referred to, define a slightly yieldable portion 34 which is protrudable through the opening 32 and provides means for attaching the display support to any suitable surface.

When using the display support it is placed on any desired supporting surface 42 as shown in Figure 4 and the portion 34 of tab 25 is firmly pressed by the fingers into engagement with the supporting surface through the opening 32. The adhesive composition 13 on the yieldable portion 34 will retain the support in place. Any suitable printed sheet, sign, tag or other article 44 to be displayed is then pressed against the adhesive coated retaining flange 12. The article 44 is thus supported for display purposes by the display support on any desired supporting surface.

The display support can be affixed to any suitable supporting surface such as glass, metal,

veneer, wood, lacquered, enameled or painted surface without marring or fouling the same and can be reattached to the same or other surfaces as often as is desired. Likewise the article attached to the flange 12 can be removed and a different article can be affixed by pressing into position with the fingers.

The blank may be formed of any suitable sheet material such as cardboard, metal foil, stiffened fabric, treated papers, and synthetically produced sheet materials made of resins and similar materials.

Figure 6 illustrates a modified construction of the blank for forming the display support where-
15 in the tab 40 is cut away at 42. When the tab is affixed to tab 25 in the same relation as described in connection with the blank shown in Figure 7, the cut away portion 42 will expose the adhesive coating on tab 25 which serves to affix
20 the support to any desired surface.

It is obvious that many modifications can be made utilizing the novel features of this invention without departing from the spirit thereof.

I claim:

- 25 1. A display support comprising a flange member having an area thereof coated with pressure sensitive adhesive composition for retaining articles for display purposes, a reinforcing member hingedly connected to said flange member, a
30 tab portion hingedly connected to said flange member and coated with a pressure sensitive adhesive composition for removably affixing the support to a supporting surface, a tab portion hingedly connected to said reinforcing member
35 and folded over into adhesive engagement with

the tab hingedly connected to the flange member the area of said tab portion being less than the area of said coated tab member.

2. A display support comprising a flange member having an area thereof coated with a pressure sensitive adhesive composition for retaining articles for display purposes, a reinforcing member hingedly connected to said flange member, a tab portion hingedly connected to said flange member and coated with a pressure sensitive adhesive composition for removably affixing the support to a supporting surface, said tab portion being provided with slits to form a yieldable portion therein, a tab portion hingedly connected to said reinforcing member and folded over into adhesive engagement with the other tab hingedly connected to the flange member and having an area thereof cut out to permit the yieldable portion of the first tab to protrude through said opening for affixing the support to a supporting surface.

3. A blank for forming a display support comprising a sheet provided with a score line to form a flange member coated with pressure sensitive adhesive composition, a tab portion hingedly connected to said flange member and forming an extension thereof, said tab member being coated with a pressure sensitive adhesive composition, a triangular reinforcing member hingedly connected to said flange member along said score line, the base of said triangular reinforcing member having hingedly connected thereto a tab portion, the area of said tab portion being less than the area of said coated tab member.

ALAN E. PRADT.
